FIRE ESCAPE

Baldwin Vale, San Francisco, Calif.

Application August 26, 1936, Serial No. 97,933

3 Claims. (Cl. 228—17.3)

This invention relates to improvements in fire escapes and more particularly to automatic extension stairs therefor.

Among the objects of the invention is to provide an inclined stair extension applicable to the conventional fire escapes, which may be normally suspended in a vertical position and automatically lowered into inclined relation to the ground and the first balcony.

10 Another object is to provide a fire escape extension stair which conforms to the regulations governing such structures, that is strong, simple, free from small and intricate parts subject to climatic deterioration and mechanical failure at critical moments.

Another object is to decelerate the descent of the stair into operative position.

Another object is to avoid the danger of injury to sidewalks and pedestrians in lowering the 20 stairs.

A further object is to divert the stair during its vertical descent to the inclined operative position just prior to the end of the descent.

Other objects and advantages will appear as 25 the description progresses.

In this specification and the accompanying drawings the invention is disclosed in its application to a conventional condition. However, it is to be understood that it is not limited to this 30 form because it may be embodied in other forms within the purview of the claims following the description.

In the three sheets of drawings:

Fig. 1 is a side elevation of a fire escape having 35 an extension stair constructed and combined therewith in accordance with this invention. The extension is shown in the operative position.

Fig. 2 is a front elevation of the same, with the extension raised into inoperative position.

40 The hand rail has been omitted in this view.

Fig. 3 is an enlarged detail in side elevation of the upper portion of the installation, showing the hoisting and suspension assembly with the head of the extension stair in the inoperative 45 position.

Fig. 4 is an end elevation of the same showing the windlass locking pawl in the operative position. The head of the stair has been omitted in this figure.

50 Fig. 5 read in conjunction with Fig. 4, shows the head of the stair in operative relation to the lower balcony bracket.

In detail the structure illustrated in the drawings referring first to Fig. 2, comprises the conventional balcony platforms 1 and 2 rigidly fixed

to the building wall 3 and having the enclosing railings such as 4 and 5, respectively. The balconies are usually constructed of conventional steel shapes, with various architectural modifications in design.

5 The interspaced standards 6 and 7 are bolted at 8 and 9 to the upper platform 1 and fastened to the top rail 4 by clamps such as 10, see Figs. 1 and 4. The U shape windlass yoke, see Fig. 3, has the cross plate 11 fixed to the standards 6 and 7 by the upper ends of the guide rods 12 and 13 between the nuts 14, 15 and 16, 17 respectively. The front extensions of the clamp 10 are also interposed between the standards 6, 7 and the plate 11, the whole assembly being drawn tight between the respective nuts 14—17, see Fig. 3.

The upward side extension 18 of the yoke has the bearing 19 for the trunnion 20 on the windlass head 21. The opposite extension 22 has the 20 square thimble 23 forced snugly through a square hole therein to provide a non-turning anchorage for the shaft 24 fixed therein by the transverse taper pin 25.

The opposite head 26 of the windlass has the 25 stuffing box 27 encircling the shaft 24 upon which it revolves freely. The windlass comprises the cylinder 28, fixed within the opposed heads 21 and 26 to form a pressure-tight cylinder freely revolvable on the trunnion 20 and the shaft 24 30 between the yoke sides 18 and 22.

The head 26 has the spur gear 29 thereon enmeshed with the pinion 30 fixed by the pin 31 on the crank shaft 32, extending through the yoke sides 18, 22 and terminating in the hand 35 crank 33. The pinion has the flange 34 bearing against the side of the gear 29 under the pressure exerted by the spring 35 when the gear and the pinion are enmeshed for rotating the windlass. The pinion 30 can be disengaged from the gear 29 by sliding the shaft 32 longitudinally and inserting a pin through the hole 36 when it is beyond the yoke side 22. This is a precautionary measure to prevent the crank 33 revolving during the unwinding of the windlass and striking an occupant of the upper balcony.

To prevent the unwinding of the windlass the pawl 37 is provided, see Fig. 4. This pawl has the pin 38 pivoted in the bearings 39, 40 formed in the plate 41, held beneath the nut 14. This 50 pawl has the teeth 42, 43 thereon adapted to mesh with the teeth on the gear 29. The pull wire 44 depending from the end of the pawl, extends through the grating of the upper platform and has the handle 45 attached thereto within easy 55

reach of an adult person on the lower platform 2. It is also advisable that it extend below the lower platform 2 and terminate in the ring 46 within reach of a fireman's hook.

5 The vertical guide rods 12, 13 extend downward and through the lower bracket 47, bolted at 48 to the lower platform 1, see Fig. 5. This bracket has the forward extension 49 through which the rods 12, 13 pass and to which they are firmly fixed by the nuts 50, 51 and 52, 53 respectively. The bracket is slit adjacent each end and the center portion 54 curved downward to form a fulcrum for the extension stair.

Referring to Fig. 2 this stair comprises the side stiles 55, 56 joined by the threads 57 at proper intervals. The length of this extension stair is equal to the distance from the first platform 1 to the ground at the usual stair inclination. The upper ends of the stiles are bent outward to form 20 the angular heads 58, 59 respectively. The respective rods 12 and 13 pass through enlarged openings in these heads to guide the descent of the stair.

The hoisting cable has its center portion or 25 bight 68 passed through the staple 61 butt welded to the periphery of the windlass cylinder 28, see Fig. 3. The cable length equal to the descent of the stair is wound around the windlass in opposite directions until its opposite extensions 62, 63 30 descend between the standards 6, 7 and are fixed in their respective heads 58, 59 as at 64, 65. The whole weight of the extension stair is thus suspended by the cable ends 62, 63 and the windlass which is locked by the pawl 37.

35 The pawl is so arranged that the windlass gear 29 must be advanced one tooth by the swing of the pawl on its center 38, so that the weight of the stair suspended thereby must be lifted before the teeth 42, 43 disengage and release the windlass.

When the windlass is thus released the weight of the suspended stair rotates the windlass to unwind the cable. The stair is guided in its descent by the vertical guide rods 12, 13; the equalized tension of the cable ends 62, 63; and by the extensions 66, 67 of the plate 49 lateral to the fulcrum 54.

This fulcrum being lateral to the longitudinal center of the width of the side stiles 55, 56, which 50 are centered on the guide rods, causes a cramping action when the stair approaches the end of its descent, see Fig. 5. This causes the lower end of the stair to swing outward to the desired inclination before coming to rest upon the ground. 55 This feature of the operation is meritorious because the path of descent of the stair is often restricted by awnings, signs and architectural projections from the wall 3. It has the further advantage that the end of the stair cannot break 60 through the side walk nor "guillotine" a pedestrian, since the out swing occurs relatively close to the ground. The progressive angle of the out-swing increases the friction against the fulcrum 54 tending to retard the descent in addition to the 65 decelerating effect of a change of direction.

Since such extension stairs weigh about six hundred pounds, more or less according to length, it is necessary to decelerate their descent. In the present instance this is accomplished by liquid 70 displacement, see Fig. 3.

The threaded portion 68 of the shaft 24 engages the running nut 69 forming the hub of a piston of any desired construction, such as the cup leather 70 clamped between the flange 71 of the 75 hub and the disk 72. The threaded portion 68 of

the shaft 24 is held stationary as previously described and has its end 73 journaled in the step bearing 74 in the head 21.

To cause the piston assembly to revolve with the cylinder-windlass 28, the rod 75 extends between 5 and engages sockets in the cylinder heads 21, 26, respectively, and passes through the piston parallel with the shaft 24. As the windlass revolves to lower the stair, the rod 75 causes the piston to revolve and advance along the thread 68 toward the head 21, displacing the oil 76 which slowly leaks between the threads 68 and where the rod 75 passes through the piston. The oil being non-compressible, the slow leakage decelerates the rotation of the windlass and the descent of the 15 stair. The rate of liquid displacement depends upon the fit of the threads, or a calibrated opening can be provided through the piston to speed up the descent. About one inch of piston travel to each foot of descent is good general practice, 20 to accomplish a speed of about two feet per second of descent. Different ratios are available by changing the pitch of the thread 68 or varying the displacement through the piston. The same 25 variations in descent speed can be also accomplished by varying the viscosity of the oil 76. While oil is preferred, a dry disk brake applied by an appropriately pitched thread 68 could be substituted for the oil displacing piston, for effecting a progressively applied frictional deceleration. 30 While they are both equivalent friction means, the oil system is preferable since the oil will continue to flow until the stair comes to rest.

The liquid displaced in descent is impounded 35 between the piston and the stuffing box 27. All working parts within the cylinder-windlass are lubricated by the oil 76.

In freezing climates it is advisable to leave an air space within the cylinder by not filling it completely with oil at the plug 77. Should the 40 guide rods 12, 13 become ice encrusted the air space within the cylinder 28 will permit the stair to drop a foot or so before the deceleration takes effect, this will cause the stair heads 58, 59 to jar the rods 12, 13 and shear off the ice 45 during the remainder of the descent. Under such conditions it is advisable to enclose the hoisting mechanism including the head of the stair in an enclosing hood 78, as in Fig. 5.

The guide rods 12, 13 join the two platforms 1, 50 2 to distribute the load between them.

This invention operates substantially as follows: The pin is removed from the hole 36 permitting the spring 35 to slide the pinion 30 into mesh with the gear 29, see Fig. 3. The stair is 55 then hoisted by turning the crank 33 to wind the cable up on the windlass 28. The operator holds the pawl 37 up in readiness to engage the gear 29 at the top of the lift. With the pawl securely holding the windlass, the shaft 32 is slid to inoperative position and held by a pin through the hole 36. During the ascent of the ladder the travel of the piston is reversed on the thread 68, 60 restoring the oil impounded behind the piston to the chamber in front of the piston. Since a cup leather is single acting in effect, the impounded oil readily passes between the cylinder wall 28 and the reversed lip of the cup leather presenting but little resistance to the hoisting operation 65 at its reduced speed.

Should occasion demand, a pull on the handle 45 will release the pawl 37, freeing the stair to descend automatically at decelerated speed to provide egress from the lower balcony platform 1. 70

While shown and described in its application to fire escapes the decelerating mechanism shown, with appropriate modifications, is equally applicable to many other uses such as ships' ladders, life boat and various other hoists.

Having thus described this invention, what is claimed and desired to be secured by Letters Patent is:

1. In combination with the upper and lower platforms of a fire escape; a pair of rigid guides terminating in a lower bracket having a fulcrum forward of said guides; a vertically movable stair engaging said guides and slidable on said fulcrum.

2. In combination with the upper and lower platforms of a fire escape; a pair of rigid guide rods extending between said platforms; a fulcrum on said lower platform forward of said guides; a stair having its head engaging said rods and its rear edge slidable on said fulcrum.

3. In combination with the upper and lower platforms of a fire escape; rigid guiding means extending between said platforms; a fulcrum on said lower platform forward of said guides; a stair engaging said guides forward of its rear edge and having its rear edge slidable on said fulcrum.

BALDWIN VALE.
